UNITED STATES PATENT OFFICE

152,592

DESIGN FOR A DECORATIVE DISPLAY LAMP OR THE LIKE

Hugh M. Carey, Glendale, Calif.

Application March 17, 1947, Serial No. 137,688

Term of patent 3½ years

(Cl. D48—20)

To all whom it may concern:

Be it known that I, Hugh M. Carey, a citizen of the United States, residing at Glendale, in the county of Los Angeles and State of California, have invented a new, original, and ornamental Design for Decorative Display Lamps or the like, of which the following is a specification, reference being had to the accompanying drawings forming part thereof.

Figure 1 is a perspective view of a decorative display lamp or the like, showing my new design, viewed from above and slightly at one side thereof.

I claim:

The ornamental design for a decorative display lamp or the like, substantially as shown.

HUGH M. CAREY.
